APPARATUS FOR MAKING PLASTIC MASSES

Walter S. Bohlman, Wilmington, Del., and David S. Bruce, Lawrence, Kans., assignors, by mesne assignments, to United States of America as represented by the Secretary of War

Application June 1, 1945, Serial No. 597,030

1 Claim. (Cl. 18—2)

1

This invention relates to an improved apparatus for making plastic masses, more particularly in the manufacture of colloided smokeless powder.

Double base smokeless powder is usually prepared by colloidizing nitrocotton and nitroglycerin with the aid of a mutual volatile solvent, such as acetone, alcohol and ether or mixtures thereof. The solvent is subsequently removed by evaporation.

The hazards of colloidizing nitrocotton-nitroglycerin mixtures without the aid of solvents, except in the special case where the nitrocotton is limited in amount to that which will readily dissolve in the nitroglycerin as in making blasting gelatin and gelatin dynamites, have resulted largely in avoidance of solventless types of processes for making such colloidized powders.

Cellulose derivatives, such as organic esters and ethers, have been plasticized by working between roll surfaces with plasticizing agents, etc. Fillers and the like are incorporated with natural and synthetic rubber by working between roll surfaces. In these cases material that drops from the rolls may be readily recovered and returned to the rolls, in fact, the material is usually stripped from the rolls by hand and returned to the rolls a number of times before complete plasticizing and/or incorporation is obtained.

The very nature of the constituents of double base powders establishes two sets of conditions not present in the referred-to cases. In the first place, the mass to be worked is very tough and stiff and difficult to work mechanically, adherence to the roll being variable and uncertain with resultant dropping of the charge from the rolls. In the second place, the operations of rolling such explosive compositions in the absence of solvents are extremely hazardous, especially on account of ignition of the material, requiring a minimum of direct personal contact (proximity) from the time of placing the material on the rolls until the mass is colloidized and removed from the rolls.

In working materials on roll assemblies to plasticize them, it is preferable to utilize two rolls rotating in opposite directions (same direction of surface motion where the cooperating surfaces are in closest proximity, one to the other), one roll having a greater surface linear velocity than that of the other. More efficient plasticizing action results from the use of such so-called differential speed rolls. However, the conditions thereof increase the importance of maintaining the mass adhered to one (the faster) of the rolls;

2

at the same time the difficulties of doing so are increased.

Furthermore, double base powder formulations generally include solid substances such as inorganic salts for purposes of reducing flash, aiding in ignition, and the like. These substances, when incorporated in the form of finely ground solid particles usually possess corrosive and/or erosive actions upon metals.

10 In attempting to adapt the usual rolls, particularly in differential speed roll assemblies, to the manufacture of double base smokeless powders, considerable difficulty has resulted from the lack of adherence between the composition and the roll surface, especially over extended periods of operation. In working smokeless powder compositions to colloid same it is required that the roll surface exhibit good adhesive properties with respect to the powder, and that this adhesiveness as well as the exact shape of the surface remain constant over an extended period of time. The subsequent molding characteristics and then the ballistics properties of the molded (extruded) powder grain are influenced by the uniformity 20 of the colloidizing step on the differential speed roll assembly. This, in turn, is determined by the degree to which the opposing roll surfaces maintain their spacial relationships and the like. In order to maintain a uniform working condition 25 on the roll assembly, it is imperative that the roll surface be highly resistant to corrosion and erosion when in use.

Now, in accordance with this invention, it has been discovered that a roll having a porous chromium surface possesses improved adherence for plastic compositions and retains this characteristic and its physical dimensions to a high degree even when subjected to corrosive and erosive actions by constituents of formulations worked 35 thereon. Further, it has been discovered that colloidable explosive compositions can be readily and advantageously colloidized by working on a roll assembly, one roll of which has a porous chromium surface.

40 Generally described, the improved roll in accordance with this invention is a hollow metallic right cylinder (with suitable axial end-supporting means and means provided for circulating a heating medium therethrough) having a surface of metallic chromium deposited thereon electrolytically, and being characterized by having a rough outer surface comprising a multiplicity of almost microscopic channels, pits, and indentations in the chromium, but not of such depth as 45 to extend in general to the underlying metal.

This roll is used preferably in combination in a two-roll assembly with a second roll having a chrome-plated surface electrodeposited on a grit-blasted metal roll.

The invention will be understood more clearly by reference to the accompanying drawing forming a part of the specification, where like numerals designate similar parts, and wherein: Fig. 1 is a front elevation of the two-roll assembly showing the powder composition adhered to the front roll, the composition being cut away in part to show the roll surface; Fig. 2 is a cross section of the roll assembly in use taken along the line 2—2 of Fig. 1; Fig. 3 is a microscopic elevational view of a section of the roll surface shown in Fig. 1; and Fig. 4 is a section taken along line 4—4 of Fig. 3. The two-roll assembly shown in Fig. 1 and Fig. 2 has a front roll 10 having an electrodeposited plating of porous chromium 11. The powder composition 12 being worked on the roll assembly is adhered to the front roll having the porous chromium surface. The back roll 14 is a metal roll having an abrasive-blasted rough surface on which is electrodeposited a plating of chromium. Suitable axial supporting means 15 are provided for the rolls and suitable journalled means 16 are provided for supplying a heating medium, such as steam, to the interior of the rolls for the purpose of maintaining the desired temperature.

As shown in the microscopic view in Fig. 3 of the porous chromium-plated surface of the front roll, the surface 11 is composed of an irregular pattern of indentations, including pits 17 and channels 19, and plateaus 20. With reference to Fig. 4, the cross section of a fragment of the porous chromium-plated front roll shows that the base metal 18 of the roll is surmounted with layer 11 of the deposited metal. The exposed surface of the layer 11, in section, is represented by a series of irregular valleys and peaks which are formed by the pits 17, the channels 19 and plateaus 20.

A roll for use in the differential rolling of a plasticizable mass, for example, an explosive composition comprising about 51% nitrocellulose, 43% nitroglycerin and 1% potassium sulfate with small percentages of a stabilizer such as diphenylamine or ethyl centralite, and a wax, such as candelilla, had a roll surface length of about 30 inches and a diameter of about 14 inches. A porous type of electroplated chromium surface was produced on this roll by electrodeposition of the chromium from a plating bath of normal constitution, a suitable bath for the deposition consisting of 250 grams of chromic acid (CrO_3) and 2.5–3.0 grams of sulfuric acid, per liter of aqueous solution. The chromium was electrodeposited on the roll by a usual method for effecting uniform electroplating of chromium and which will be well known to one familiar with the art.

After the electroplate was deposited on the roll surface, the plating was etched anodically in a similar solution, following the method of U. S. Patent No. 2,314,604. By this method, the porosity of the plate was developed to yield a chromium surface having a multiplicity of microscopic grooves, pits or depressions.

The chromium-plated roll produced by this method had a chromium plate thickness of about 0.004 inch with a maximum porosity depth of the order of about 0.001 inch. This roll, when used in a roll assembly for working the explosive composition described hereinabove, gave unex-

pectedly good results as compared with those obtained by the use of the usual rolls for working plastic masses.

The adherence of the composition to the porous chromium roll surface was increased greatly and remained uniform over the entire surface. Further, no "slick" areas developed, characterized by low adhesion with the material, as was true of other surfaces previously roughened by the use of abrasives, etc.

The procedure for colloiding a nitrocellulose-nitroglycerin powder in accordance with this invention is illustrated by the following description. Fifty-one parts of nitrocellulose (13.25% N) of lint base, about 43 parts of nitroglycerin, about 3 parts of diethyl phthalate, about 1 part of ethyl centralite, all parts by weight, and a small amount of carbon black and candelilla wax, were made into a wet paste by known methods. The wet paste was air dried to about 12–14% moisture content and then blended and uniformly mixed with about one part by weight of crushed solid potassium sulfate to give the final dry paste.

The dry paste was dumped from a fiber bucket, in a 6-pound charge, onto a set of differential speed rolls, which rolls were 14 inches in diameter, and 30 inches long, and maintained at 210° F. by circulating hot water. The rolls were horizontally disposed and the front or faster roll, which was a roll in accordance with this invention and had a porous-type chromium-plated surface, rotated at 31 R. P. M. (114 feet per minute) and the differential ratio was 1.2:1. The back roll had a chrome plate electrodeposited on a grit-blasted metal roll.

The composition was thus subjected to periodic or cyclically changing pressure and shearing actions as it adhered to and moved with the porous chromium-plated roll surface, being alternately passed through confined zone and an unconfined zone. The rolling time was 2½ minutes and the sheet thickness was 0.065–0.070 inch. The sheet of explosive composition was formed on the front or faster roll with excellent adherence and, at the end of the rolling time, the sheet was cut off by means of a remotely controlled air-operated doctor blade. The sheet was carried by an automatic conveyor past cooling air blasts to a transfer trough. The excellent adherence of the composition to the front roll made it unnecessary for the operator to return to the machine to re-feed any fragments of the initial charge.

The foregoing explosive composition formed a very tough, stiff, colloided mass. Experience has shown such formulations to be exceedingly difficult to work on the usual differential speed rolls, considerable difficulty being experienced in preventing the material from falling from the rolls. The improvement in accordance with the present invention can be attributed, in part, to the greater adhesiveness between the explosive composition and the porous chromium surface.

The porous chromium-plated roll may be used with advantage in working and colloiding other formulations as well. The porous chromium surface is particularly advantageous with other mixtures when they contain finely-ground solid particles, such as potassium sulfate, potassium nitrate, etc. The increased hardness of the plate reduces the wearing action of the solid thereon which possibly accounts partially for so-called "slick" areas.

It may be observed that where "slick" areas develop, the composition may even shift to and move with the back roll.

The porous chromium electroplate may be prepared by developing a normal hard chromium plate on the underlying metal and then etching by chemical and/or electrochemical methods, the conditions selected for developing the porosity of the chromium plate being determined by the particular type of porosity desired. The most advantageous porosity will depend upon the physical nature of the composition to be worked.

In working the mass described above, it is preferred to use a porous chromium surface having plateaus with relatively small areas (pitted-type). With compositions producing less stiff and less tough colloided masses, surfaces with larger plateau areas (channel-type) are satisfactory.

It is preferred to use as the back roll, a grit- or abrasive-blasted chromium-plated roll. It will be understood that this type of chromium surface is rough, the indentations in the underlying metal produced by the grit blasting being reflected in the chromium plate electrodeposited thereon. such a chromium surface, although it exhibits a certain amount of porosity, is to be distinguished, for the purposes of description herein and use in the appended claim, from the porous type of surface produced by electrodeposition on a normal surface followed by chemical and electrochemical etching separately or in combination and referred to herein as porous chromium electroplate.

The combination of a grit-blasted chromium-plated back roll with a pitted-type porous chromium-plated front or faster roll has been found to be especially advantageous in working stiff and tough compositions in that there are good positive feeding action (bite), excellent adhesion over a long period of time, and improved colloiding action on the composition while being worked.

Thus, an improved method has been discovered for colloiding or plasticizing colloidal mixtures, such as smokeless powder compositions, on roll assemblies, which comprises working the mixture on a differential speed roll assembly, the faster roll having a porous chromium electroplated surface with a high degree of affinity or improved adhesiveness for the material being colloided whereby it is held onto and carried by the faster roll and is more efficiently colloided and with considerably less hazard. The porous chromium-plated roll gives an improved plasticizing effect on plastic or plasticizable masses and is especially useful in differential speed rolling because of its

greater adhesiveness for stiff colloidal materials, its resistance to corrosion, and its resistance to abrasion.

What we claim and desire to protect by Letters Patent is:

A differential speed roll assembly which comprises a pair of rolls adapted to rotate in opposite directions, one of said rolls adapted to rotate with a greater surface linear velocity than the other of said rolls, said one of said rolls being provided with an outside surface of porous chromium electroplate characterized by high resistance to corrosion and erosion and having an improved adherence for a nitrocellulose-nitroglycerin powder composition, and said other of said rolls being provided with a chromium electroplate deposited on an abrasive-blasted metallic surface.
